US0D1057274S

(12) **United States Design Patent** (10) **Patent No.:** **US D1,057,274 S**
Tung (45) **Date of Patent:** **** Jan. 7, 2025**

(54) **CASE FOR SMOKERS' ACCESSORY**

- (71) Applicant: **Philip Morris Products S.A.**,
 Neuchâtel (CH)
- (72) Inventor: **Jeffrey Tung**, San Francisco, CA (US)
- (73) Assignee: **Philip Morris Products S.A.**,
 Neuchâtel (CH)
- (**) Term: **15 Years**
- (21) Appl. No.: **29/935,818**
- (22) Filed: **Apr. 3, 2024**

Related U.S. Application Data

- (62) Division of application No. 29/789,590, filed on Oct. 1, 2021, now Pat. No. Des. 1,028,342.
